UNITED STATES PATENT OFFICE

2,652,256

WHIP ACTION DEVICE FOR THE HEAD OF
GOLF CLUBS

Wilbur H. Thomas, Costa Mesa, Calif.

Application September 14, 1951, Serial No. 246,577

3 Claims. (Cl. 273—170)

1

This invention relates to golf clubs, and more particularly to an improved adjustable weight device for the head of a golf club.

The main object of the invention is to provide a novel and improved weight adjusting means for the head of a golf club which involves very simple parts, which is readily installed on the head of a golf club, and which is easy to adjust to provide proper balance of the club in accordance with the particular requirements of the player using the club.

A further object of the invention is to provide an improved golf club having means for adjusting the center of gravity of the head of the club in accordance with the individual requirements of the player using the club and to correct defects in the player's swing, the improved means involving relatively inexpensive components, being compact in size, being easy to manipulate, and enabling the player to set the position of the center of gravity of the club head in accordance with his particular type of swing.

Further objects and advantages of the invention will become apparent from the following description and claims, and from the accompanying drawings, wherein:

Figure 1 is a side elevational view of the head of an improved golf club according to the present invention showing one form of weight-adjusting means provided on the head;

Figure 2 is a front elevational view of the portion of the golf club of Figure 1;

Figure 3 is a horizontal cross sectional detail view taken on the line 3—3 of Figure 1;

Figure 4 is a fragmentary side elevational view, similar to Figure 1, but showing another form of weight-adjusting means according to the present invention; and

Figure 5 is a vertical cross sectional view taken on the line 5—5 of Figure 4.

Referring to the drawings, and more particular to Figures 1, 2 and 3, 11 designates a golf club having the head 12 projecting laterally from the lower end of the shank portion 13. The head is generally conventional in shape. Designated at 15 is a headed machine screw threadedly engaged with the intermediate portion of the club head 12. Designated at 16 is a resilient arm formed with a longitudinal slot 17. The shank of the screw 15 passes through the slot 17, whereby the arm 16 is adjustable in position along the club head 12 and may be clamped in any desired adjusted position by tightening the screw 15. Secured to the end of the arm 16 is a circular weight 18 of any suitable heavy material, said weight having a

2

shank portion 19 extending through an opening in an end of the arm 16 and being formed with an abutment 20, as by peening over the peripheral portions of the shank 19 to secure the weight 18 to the arm 16. The abutment 20 engages the surface of the club head 12 and maintains the weight 18 and the end portion of the arm 16 spaced away from the surface of the club head. Since the arm 16 is of resilient material, when the club is swung, the weight 18 flexes outwardly during the swing and provides an added amount of "whip" action, degree of which may be adjusted in accordance with the effective length of flexible arm 16. This of course is determined by the position on which the head of screw 15 engages said arm. By a series of trials, the individual player may readily determine the best position in which to clamp the arm 16 to provide a desired setting of the effective center of gravity of the club head. The position of the effective center of gravity of the club head is of course determined by the position in which the weight element 18 is secured relative to the remainder of the head 12.

In the embodiment of the invention shown in Figures 4 and 5, the club head, designated at 12', is formed with a longitudinal, rectangular groove or recess 21, the passing screw 15 being located in the intermediate portion of the recess 21. The resilient arm 16 is received in the recess 21 and the screw 15 passes through the slot 17 of said arm, whereby the arm 16 may be clamped in any desired adjusted position along the recess 21. As shown in Figure 5, the weight element 18 is normally spaced away from the rear surface of the club head 12', as in the case of the structure shown in Figures 1, 2 and 3, by the abutment element 20, which engages the club head 12' and functions as a spacer to establish the normal position of the weight element 18 relative to the remainder of the club head. The recess 21 acts as a guide means and serves to prevent the arm 16 from pivoting away from its adjusted position during the swing of the player and serves to maintain the weight element 18 in its adjusted position after the screw 15 has been clamped tight.

While certain specific embodiments of an improved adjustable golf club have been disclosed in the foregoing description, it is to be understood that the various modifications within the spirit of the invention may occur to those skilled in the art. Therefore it is intended that no limitations be placed on the invention except as defined by the scope of the appended claims.

What is claimed is:

1. In a golf club, a shank, a head projecting laterally from said shank, a headed fastening member threadedly engaged with said head at its rear surface, an arm of resilient material formed adjacent one end with a longitudinal slot, said fastening member extending through the slot, whereby the arm is adjustably secured to said head adjacent said one end thereof, and a weight member secured to said arm adjacent its other end, whereby the weight member flexes outwardly during a swing of the club, providing a whip action, the degree of which can be adjusted by adjusting the position of the slot relative to said headed fastening member.
2. In a golf club, a shank, a head projecting laterally from said shank, a headed fastening member threadedly engaged with said head at its rear surface, an arm of resilient material formed adjacent one end with a longitudinal slot, said fastening member extending through the slot, whereby the arm is adjustably secured to the other said head, a weight member secured to the other end portion of said arm, and an abutment element on said other end portion between the weight member and said arm, maintaining said other end portion spaced from the rear surface of the head, whereby the weight member flexes outwardly during a swing of the club, providing a whip action, the degree of which can be adjusted by adjusting the position of the slot relative to said headed fastening member.
3. In a golf club, a shank, a head projecting

4

laterally from said shank, said head being formed with a groove in its rear surface, a headed fastening member threadedly engaged with said head in said groove, an arm of resilient material slidably mounted in said groove, said arm being formed with a longitudinal slot adjacent one end, said fastening member extending through the slot, whereby the portion of the arm adjacent said one end is adjustably secured to said head, a weight member secured to the other end portion of said arm, and an abutment element on said other end portion between the weight member and said arm, maintaining said weight portion spaced from the rear surface of the head, whereby the weight member flexes outwardly during a swing of the club, providing a whip action, the degree of which can be adjusted by adjusting the position of the slot relative to said headed fastening member.

WILBUR H. THOMAS.
